UNITED STATES PATENT OFFICE.

HANNAH THOMAS, OF CANAL DOVER, OHIO, ADMINISTRATRIX OF WILLIAM J. THOMAS, DECEASED.

KILN FOR BURNING BRICK.

SPECIFICATION forming part of Letters Patent No. 592,842, dated November 2, 1897.

Application filed March 30, 1896. Serial No. 585,378. (No model.)

To all whom it may concern:

Be it known that WILLIAM J. THOMAS, deceased, late a citizen of the United States, residing at Canal Dover, in the county of Tuscarawas and State of Ohio, did in his lifetime invent certain new and useful Improvements in Kilns for Burning Brick, &c., of which the following is a full, clear, and exact description.

This invention relates to improvements in up-and-down draft kilns for burning brick, tile, and other clay products, the primary object being to utilize the heat of the furnaces to the best advantage and to uniformly burn and shade the products treated in the kiln; and the invention consists in certain features of construction and combinations of parts and the peculiar connection of two kilns with each other, hereinafter described, and pointed out in the claims.

20 In the accompanying drawings, Figure 1 is a top plan in horizontal section of two connected kilns embodying the invention. Fig. 2 is a top plan in horizontal section below the floor-line. Fig. 3 is a vertical section on lines 3 3, Figs. 1 and 2; and Fig. 4 is a vertical section on line 4 4, Figs. 2 and 3.

Referring to the drawings, A A' designate two circular kilns located a suitable distance apart.

30 Referring to either one of the kilns, B represents the fires or furnaces for said kiln. Said fires or furnaces are located at suitable intervals about the kiln. An upright flue C is located at the rear of each furnace and the combustion-chamber of the furnace is in open relation with said flue. Flues C discharge upwardly into the kiln, preferably about midway of the height of the kiln. The kiln at or near the central portion thereof is provided with a transversely-arranged partition or wall D, that divides the lower portion of the kiln into two rooms or chambers a a', in which the brick, tile, or other clay products are placed for burning. Flues E, arranged 40 parallel with wall D, are provided below the floor of the kiln and are in open relation with the interior of the kiln by means of holes or perforations a² in the floors of chambers a a' of the kiln. The two flues E, that are located 45 next adjacent to partition or wall D, are placed in open relation with the interior of

the kiln by means of ducts d, formed in said wall or partition at suitable intervals longitudinally of said wall. Two comparatively large flues G G' are arranged transversely of 55 and below the different chambers a a', respectively—that is, the two flues G G' of the kiln are arranged at opposite sides, respectively, of and preferably at right angles to the wall or partition D of the kiln. Each flue G G' is 60 in open relation by means of holes or perforations g, formed in its top wall, with the flues E below the kiln-chamber above, and consequently is in open relation with said chamber. Flues G G' at their outer ends communicate with different flues H H', respectively, that converge toward the stack or chimney I, and are connected at their meeting ends with said chimney by a short duct K. Duct K is provided with a damper K' for controlling 70 communication between flues H H' and the chimney. A damper H² is located at the meeting ends of the two flues H H' and is adapted to interrupt communication between either one of said flues H H' and duct K without interference with the communication between the other flue and said duct K.

By the construction hereinbefore described it will be observed that the products of combustion or heating agent from the furnaces 80 are caused to pass from the upright flues at the rear of said furnaces downwardly through kiln-chamber a or chamber a', according as a draft from the kiln to the chimney is created through flue H or flue H', and that the 85 products of combustion or heating agent, by a proper manipulation of damper H², can be passed through the kiln in opposite directions alternately, so that the heating agent is caused to pass up and down alternately 90 through each kiln-chamber and the bricks or ware burned in said chamber—that is, by the proper manipulation of the dampers the heating agent from one of the kilns, say, for instance, kiln A, is received below the floor 95 of the kiln A' and passes upwardly through the kiln-chambers a, over the partition or dividing wall between the two kiln-chambers, and then downwardly through the other kiln-chamber for a short interval of time, and then. 100 by manipulating the dampers the draft is reversed, so as to cause the heating agent at the

bottom or below the floor of the last-mentioned chamber to ascend said chamber, and thence pass over the dividing-wall and downwardly through the first-mentioned chamber 5 for a short interval of time, and then the draft is again reversed, and so on during the operation of the kiln until the burning of the bricks or ware within the kiln is completed. The damper K' within duct K is of course left 10 open during the hereinbefore-described operation of the kiln. By the improved method hereinbefore described and involving an up-draft and downdraft alternately through the chambers of the kiln and reversing the draft 15 at short intervals of time the best results are obtained and the bricks or ware in the lower portion and upper portion of said chamber are uniformly burned and the burning of each brick or piece of ware is uniform top 20 and bottom. It will also be observed that the chimney is located centrally between the two kilns; that the two flues H H' of each kiln converge toward the chimney, as already indicated; that flues H H' of the different kilns 25 converge toward the chimney and are connected together by a flue L; that flues H' H'' of the kilns also converge toward the chimney and are connected together by a flue L', and that each flue L and L' is provided with 30 a damper L² for controlling communication therethrough.

By the arrangement of kilns and flues just described the space occupied by them is reduced to a minimum and the heating agent 35 from one of the kilns can be conducted to the other kiln, a continuous draft can be established through the two kilns, and said continuous draft can be reversed at pleasure and an updraft and a downdraft can be created alternately through the chambers of the kilns. For instance, by closing damper K' of kiln A, interrupting communication between flue H and duct K of said kiln, closing damper L² in flue L, opening damper L² in flue L', interrupting 40 communication between flue H' and duct K of kiln A', and opening damper K' of said kiln A' the heating agent from kiln A is transferred to kiln A' and passes upwardly 45 through chamber a' of said kiln A', over the dividing-wall between the two chambers of said kiln A', and then downwardly through chamber a of said kiln A'. (See Fig. 2.) By interrupting communication between flue H' and duct K of kiln A, closing damper K' of 50 said duct K, closing damper L² of flue L', opening damper L² of flue L, interrupting communication between flue H and duct K of kiln A', and opening damper K' of said kiln A' the heating agent is transferred from kiln 55 A to kiln A' and passes upwardly through chamber a of said kiln A', over the dividing-wall between the chambers of said kiln A', and then downwardly through chamber a' of said kiln A'. Hence it will be observed that 60 65 in transferring the products of combustion or heating agent from one kiln, after the completion of the burning operation in said kiln,

to the other kiln, one-half of the heating agent of the heat-discharging kiln can be conducted through the recipient kiln in the one 70 direction and the other half of said heating agent can be conducted through the recipient kiln in the opposite direction, and hence the products of combustion can be conducted upwardly and downwardly alternately through 75 the chambers of said last-mentioned kiln.

By interrupting communication between flue H' and duct K of kiln A', closing damper K' of said kiln, closing damper L² of flue L, opening damper L² of flue L', interrupting communication between flue H' and duct K of kiln A, and opening damper K' of said kiln A the products of combustion or heat are transferred from kiln A' to kiln A and passes upwardly through chamber a' of said kiln A, over the 80 dividing-wall between the two chambers of said kiln A, and then downwardly through chamber a of said kiln A. By closing damper L² of flue L', interrupting communication between flue H' and duct K of kiln A', closing 85 damper K' of said kiln, opening damper L² of flue L, interrupting communication between flue H and duct K of kiln A, and opening damper K' of said last-mentioned duct 90 the products of combustion or heat are transferred from kiln A' to kiln A and passes upwardly through chamber a of said kiln A, over the dividing-wall between the two chambers of 95 said kiln A, and then downwardly through chamber a' of said kiln A.

It will therefore be observed that by a proper manipulation of the different dampers the heating agent can be passed from kiln A to kiln A', and vice versa, alternately, in opposite directions, and admirable results are 100 obtained by passing the products of combustion between the two kilns at short intervals of time and passing them upwardly and downwardly alternately through the different chambers of the kilns.

It will of course be understood that dampers L² of flues L and L' are closed in the operation of the kilns independently of each other.

M designates doorways affording access to the chambers of the kilns and closed in any 105 approved manner during the operation of the kilns, and O represents the openings in the tops of the kilns for accommodating the escape of vapors arising during the water-smoking of ware burned in the kilns.

What is claimed is as follows:

1. A circular kiln having two chambers a a' in open relation with each other at the top; fires or furnaces arranged radially at intervals entirely around the kiln; upright flues 115 in open relation with the furnaces' combustion-chambers and discharging into the kiln; a transversely-arranged wall D for dividing the chambers a a'; flues E arranged parallel with said wall and communicating with said chambers a a' by means of holes or perforations in the kiln-floor; two flues G G' located below said flues E, each of said flues G G' communicating with the flues E by means of 125

holes in its top wall; said flues G G' being arranged at opposite sides and at right angles to the wall D; a chimney; two flues H H' leading from the flues G G', respectively, and connected with the chimney, and means for interrupting communication between either one of said flues H H' and the chimney without interfering with the communication between the other of said flues and the chimney, substantially as described and for the purpose specified.

2. Two circular kilns arranged a suitable distance apart, and each comprising fires or furnaces B arranged at intervals entirely around the kiln; upright flues in open relation with the furnaces' combustion-chambers and discharging into the kiln; two chambers a a' in open relation with each other at the top; a transversely-arranged wall D for dividing said chambers a a'; flues E arranged below the floors of the kiln-chambers parallel with said wall D and in open relation by means of perforations in the kiln-floor with the kiln-chamber above; two flues G G' located below said flues E each flue G G' communicating with flues E below the floor of the different kiln-chambers by means of holes in its top wall, and each flue G G' being arranged at opposite sides and at right angles to said wall D; a chimney; the two flues H H' leading from the different flues G G' respectively, in combination with a chimney located between the two kilns, said flues H H' converging toward said chimney and communicating therewith, a duct connecting the flues H H' with the chimney, and dampers for controlling the passage of the products of combustion through the several flues.

3. A circular kiln having fires or furnaces B arranged at suitable intervals entirely around the kiln; upright flues C in open relation with the combustion-chambers of said furnaces, and discharging into the kiln; a transversely-arranged wall for dividing the chambers a a', said wall being provided at intervals with ducts d arranged alternately at opposite sides of the wall; flues E arranged below the floor of each kiln-chamber and in open relation at different points with the respective kiln-chamber by means of holes or perforations in the kiln-floor; two flues G G' arranged in under flues E and in open relation with said flues E, at different points by means of holes in the top of each flue G G'; flues H H' leading from the outer ends of the different flues G G', respectively, to and converging toward

and connected with the chimney, and a damper H² arranged at the meeting ends of said flues H H' and capable of interrupting communication between either one of said flues and the chimney without interrupting communication between the other of said flues and the chimney, substantially as set forth and described.

4. Two circular kilns arranged a suitable distance apart, and each of said kilns provided with the following elements: fires or furnaces B; upright flues in open relation with the furnaces' combustion-chambers and discharging into the kiln; two chambers a a' in open relation with each other at the top; a transversely-arranged wall D for dividing said chambers a a'; flues E located parallel with said wall below the kiln-floor and communicating through holes in the floor with the chambers a a'; two flues G G' arranged below the flues E and at right angles to both the walls D and said flues E, and communicating with the latter by means of holes in the top wall of each flue G G'; in combination with a chimney arranged centrally between the two kilns; two flues H H' leading from the different flues G G' of each kiln to and converging toward said chimney; a short duct K connecting the flues of each pair of converging flues H H' with the chimney, and provided with a damper K'; a damper H² arranged at the meeting ends of each pair of converging flues H H' and capable of interrupting communication between either one of said converging flues and the chimney without interrupting communication between the other of said flues and the chimney; the flue L connecting together the flues H H of the different kilns and provided with a damper L², and the flue L' connecting together the flues H H' of the different kilns and provided with a damper L² all arranged and operating substantially as shown, for the purpose specified.

In testimony whereof I, HANNAH THOMAS, administratrix of the estate of WILLIAM J. THOMAS, deceased, have signed my name to this specification, in the presence of two subscribing witnesses, this 21st day of March, 1896.

HANNAH THOMAS,
Administratrix of the estate of William J.

Thomas.
